(57) **CLAIM**

The ornamental design for a panel portion for an electronics rack, as shown and described.

DESCRIPTION

FIG. 1 is a perspective view of a panel portion for an electronics rack according to one embodiment of the invention.

FIG. 2 is a front view of the panel portion of FIG. 1.

FIG. 3 is a rear view of the panel portion of FIG. 1.

FIG. 4 is a top view of the panel portion of FIG. 1.

FIG. 5 is a bottom view of the panel portion of FIG. 1.

FIG. 6 is a left side view of the panel portion of FIG. 1.

FIG. 7 is a right side view of the panel portion of FIG. 1.

FIG. 8 is a cross sectional view of the panel portion of FIG.

1 taken along lines 8-8 in FIG. 2; and,

FIG. 9 is an enlarged segment of the perspective view of the panel portion of FIG. 1 illustrating the surface contour.

The dash-dot break lines that represent the bounds of the claim. The portions of the drawings appearing in broken lines are for environment only and do not form a part of the claimed design.

1 Claim, 6 Drawing Sheets
